AUTOMOBILE FENDER TRIM

Carl E. Sykes, Norfolk, Va.

Application May 24, 1949, Serial No. 2,837

Term of patent 14 years

(Cl. D14—6)

To all whom it may concern:

Be it known that I, Carl E. Sykes, a citizen of the United States, residing at Norfolk, county of Norfolk, and State of Virginia, have invented a new, original, and ornamental Design for Automobile Fender Trim, of which the following is a specification, reference being had to the accompanying drawing, forming part thereof, and wherein:

Fig. 1 is a front perspective view of an automobile fender trim, showing my new design;

Fig. 2 is a front elevational view; and

Fig. 3 is a sectional view taken on line 3—3 and looking in the direction of the arrows.

I claim:

The ornamental design for an automobile fender trim, substantially as shown.

CARL E. SYKES.
